GRAB TOOL

Wayne N. Sutliff, Bakersfield, Calif.

Application March 8, 1949, Serial No. 80,165

5 Claims. (Cl. 294—86)

1

This invention relates to an oil well tool, and particularly pertains to a grab tool.

In oil well production it often occurs that broken parts of metal are lost in the well bore and that these parts interfere with the drilling operations and impair the cutting edges of the drill tools. It is desirable to withdraw these parts from the well by mechanical means. Heretofore it has been common practice to operate a suction bailer and withdraw small parts from the well bore. This, however, does not provide a tool which will grasp relatively large or cumbersome parts and pull them to the surface. It is the object of the present invention, therefore, to provide a grab tool which may be lowered to the bottom of a well and which may be operated mechanically so that the tool may be caused to grasp a loose object in the bottom of the well and to hold the article so that the article may be drawn from the well without losing it and insuring its safe recovery. In the same operation of oil well production it often occurs that there is difficulty in removing a valve ball from its seat. Various tools have been provided in an attempt to grasp the spherical mass of valve ball and to hold the ball while it is elevated from its seat. It is the principal object of the present invention, therefore, to provide a grab structure which will not only grasp loose extraneous material in the bottom of a well but will also act to pick up smooth spherical members which may be disposed upon a special seat.

The present invention contemplates the provision of a suspending member and a pair of grab arms or fingers which may be manipulated mechanically to be moved toward each other or separated as desired in grasping an article to be retrieved from the well.

The invention is illustrated by way of example in the accompanying drawing in which:

Figure 1 is in a view in longitudinal section and elevation showing one form of the present invention and indicating the manner in which the grab fingers are mounted and manipulated, the figure showing by dotted lines the contracted position of the grab fingers.

Fig. 2 is an enlarged view in vertical section and elevation showing the manner in which the structure is adapted for use in lifting a valve ball from its seat.

Referring more particularly to the drawing, 10 indicates a supporting string. This may be provided with a pin or otherwise constructed although it is here shown as fitted with a sub 11. The sub 11 is formed with a central opening 12

2

which receives a nut 13. A reduced bore 14 is formed at the lower end of the sub. Extending through the reduced bore 14 is a mandrel 15, the upper end of which is threaded to receive the nut 13. At the lower end of the mandrel is a pivotal head 16 which receives pins 17 and 18. These pins provide a pivotal mounting for grab elements 19 and 20. The grab elements 19 and 20 are formed with lower grab arms 21 and upper lever arms 22. The upper lever arms are free to swing and are formed with inclined cam faces 23 which rest against the wedge face of a frustococonical seat 24 by which the lever arms are swung. A spring 25 engages the two lever arms 22 and tends to draw them toward each other. The lower grab arms 21 are formed with fingers 26 which extend inwardly toward each other and act as claw fingers to engage any member which is free in the well bore and is to be grappled.

The grab elements 19 and 20 and the head 16 are enclosed within a cylindrical and tubular housing 27. This housing is externally threaded at its upper end and extends into a threaded end 28 of a weight structure 29. This structure is preferably cylindrical and has a central bore 30 through which the mandrel 15 extends. The lower end of the housing 27 is enlarged as indicated at 31. This forms an inclined shoulder and an enlarged portion which reciprocates within the cylindrical portion of a trip ring 32. The trip ring 32 has a bore 33 which agrees substantially in diameter with the outside diameter of the housing 27 and the lower enlarged portion 34 which accommodates the enlarged portion 31 of the housing 27. This portion 31 reciprocates therein. It will be seen that the enlarged portion 34 of the trip ring 32 provides a shoulder which is encountered by the enlarged end 31 of the housing 27. Thus the trip ring 32 cannot be withdrawn or removed from the housing. Extending downwardly from the ring 32 is a series of supporting legs 35 which are spaced from each other circumferentially around the lower edge of the trip ring 32. These legs are substantially triangular in shape and thus give sufficient clearance for the fingers 26 as they move downwardly. It is also obvious that the length of the legs 35 is sufficient to insure that the fingers will be positioned properly relative to any object resting upon the lower end of the open well bore so that these fingers may move around the objects and tend to grapple them. In order to hold the trip ring 32 temporarily the lower circumferential edges 36 of the trip ring

are slightly bevelled and bear against lock balls 37 which are mounted within upwardly and outwardly inclined pockets 38. These pockets are closed at their outer ends by threaded plugs 39 and accommodate helical springs 40 which are interposed between the plugs 39 and the lock balls 37.

In the form of the invention shown in Fig. 2 of the drawing a tubing 41 is provided. A plurality of friction springs 42 are mounted to reciprocate within the central bore of the tubing 41. These are carried upon a sleeve 43 which reciprocates upon a mandrel 44. The mandrel 44 is formed with a reduced cylindrical portion 45 upon its upper end and a threaded box 46 at its lower end. The upper end of the cylindrical portion 45 is externally threaded and receives a nut 47 which is housed within a bumper sleeve 48. The upper end of the bumper sleeve is provided with a sub or other suitable connection 49. The body member 44 carries a plurality of latch fingers 50 which are mounted upon the sleeve 43 and temporarily hold the friction spring fingers 42 in their innermost position. The nut 47 has a central bore which receives the bumper sleeve 48. This sleeve is formed with a central opening 51 through which the reduced portion 45 of the member 44 reciprocates.

Mounted upon the lower end of the mandrel 44 is a body member 52 which is formed with a pin 53 extending within the box 46. The body member reciprocates within the sleeve 43 and extends beyond the lower end thereof. Mounted upon the body member 52 is a plurality of spring grab fingers 54. These grab fingers have straight portions which lie in longitudinal grooves in the body member 52 and arcuate free portions 55 which act as grab fingers and may fit around the valve ball 56 which is mounted upon the valve seat 57. It is obvious that by this arrangement the grab fingers 54 will be forced around the ball 56 and will draw itself inwardly to grip the ball while wedging it off of its seat 57 and to a holding position, as indicated by dotted lines in Fig. 2.

In operation of the device shown in Fig. 1 of the drawing the mandrel 15 is either mounted on the sub 11, which is attached to a stem, or to a cable not shown in the drawing. In any event the sub 11 is suspended in the well and the entire structure is lowered. It is obvious that at this time the head 16 and the grab elements 18 and 20 are in their retracted position within the housing 27. At this time the ends 23 of the lever extensions 22 will be drawn upwardly against the tapered cone face 24 and the fingers 26 will be drawn together. The trip ring 32 is also slipped upwardly on the housing 27, so that the shoulders on the enlarged portion 31 of the housing and the shoulders of the trip ring will limit downward movement of the trip ring. At this time the tapered faces 36 of the housing 27 will be retracted and the lock balls 37 will be forced downwardly by the springs 40 into the path of travel of the inclined faces 36 so that the trip ring will be held in its uppermost position temporarily. The entire grab structure is lowered into the well until the legs 35 rest upon the lower end of the well bore. At this time the housing 27 will dispose its weight downwardly and will be held against movement relative to the legs by the lock balls 37. Attention is directed to the fact that the lock balls are mounted in the inclined bores or pockets 38 and that the lower end of the housing bears against the lock

balls. In view of this inclined position of the bores 38 the lock balls will move downwardly by gravity and obstruct the downward movement of the housing. At the same time the member 11 will move downwardly and will relieve the mandrel 15. This will permit the mandrel 15 and the nut 13 to move downwardly carrying the member 16 and the grab arms. The portions 26 of the grab arms will then move downwardly into the space between the legs 35 to encounter an object to be grappled. At this time the spring 25 and the expander 16 will tend to act upon the arm 22 and swing the grab arms 26 outwardly in the space defined by the legs 35. When it is desired to grasp or grapple an object which is to be retrieved, the member 11 is moved down further until the stop-weight 29 is encountered. This will impose weight upon the housing 27 and will cause it to act against the lock balls 37 forcing them rearwardly and upwardly in a non-locking position and permitting the lower end of the housing 27 to pass downwardly between the legs 35. At this time there will be a tendency for the arms 26 to swing inwardly in the direction of the arrow —a— as shown in Fig. 1. When it is desired to draw the arms 26 together, the member 11 is lifted until the nut 13 is engaged after which the mandrel 15 is lifted. This will raise the portion 16 and pull the arms 26 into the housing 27. By the action the arms 26 will grasp an object to be retrieved from the bottom of the well bore.

In the form of the invention shown in Fig. 2 of the drawing the device is intended to be used for removing the valve ball 56 from its seat 57. In this case the spring members 42 are locked in position by slipping their free ends under the members 50. The spring members 42 will then engage the tubing 41 and allow the device to be lowered into the tubing until such time as it is desired to encounter the ball 56. The structure is then lifted by suitable supporting means which will act to lift the bumper sleeve 48. This will engage the nut 47 and lift the mandrel 44 until the shoulder formed by its reduced portion 45 strikes the end of the sleeve 43. When this is done the members 50 will be lifted from their locking engagement with the springs 42 so that upon further lowering the mandrel will move downwardly and the spring fingers 45 will drop over the ball 56 and catch it.

It will thus be seen that the structures here disclosed provide simple means for grappling loose parts in a well bore or a loose valve ball, and insuring that these members will be elevated to the surface of the well, and will act effectively as a grab or fishing tool.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

1. A fishing tool comprising a tubular body member, a plurality of grab fingers reciprocably mounted within the tubular member and adapted to be retracted to a non-grabbing position, latch means for supporting the body member above the lower end of the well bore whereby when the weight of the body member is imposed upon the supporting member the latch means will release the body member permitting it to move downwardly, and means acting upon the grab mem-

bers forcing them into grabbing position when the body member is free to move relative to its support.

2. A fishing tool comprising a cylindrical housing, a plurality of grab fingers, a mandrel free to reciprocate through the housing and providing a pivotal support for the grab fingers, yieldable means tending to hold the grab fingers in their non-grabbing position, and weighted means acting to positively move the fingers to their grabbing position as controlled by the fishing tool suspension means.

3. A fishing tool comprising a cylindrical housing, a plurality of grab fingers, a mandrel free to reciprocate through the housing and providing a pivotal support for the grab fingers, yieldable means tending to hold the grab fingers in their non-grabbing position, weighted means acting to positively move the fingers to their grabbing position as controlled by the fishing tool suspension means, a supporting member mounted upon said housing to engage the lower end of the well bore and hold the lower end of the housing in spaced relation to the well bore, and latch means temporarily holding the housing and supporting means against movement with each other and acting to release the housing when weight is imposed thereon.

4. A fishing tool comprising a sub structure adapted to be attached to a suspending element, a mandrel relatively movable with said sub structure as the sub is lowered into the well, a

tubular housing through which the mandrel extends vertically and with which it has relative vertical movement, a plurality of grab fingers pivotally mounted at points intermediate their ends to said mandrel and normally disposed within said housing, yieldable means connected to the upper free ends of said grab fingers and acting to swing the lower free ends of said grab fingers outwardly against the housing to limit the outward movement of said grab fingers, and a wedge-shaped member freely mounted upon said mandrel and within the housing, said wedge-shaped member engaging the upper free ends of the grab finger structures to force the lower ends of the grab fingers outwardly.

5. The structure of claim 4 including spacing means into which the housing telescopes, the lower end of said spacing means resting upon the end of the well bore, and latch means acting between the housing and the spacing means tending to hold the spacing means against telescoping movement until the weight of the grab structure is imposed thereon.
